GIFT PACKAGE ORNAMENT DISPLAY OR SIMILAR ARTICLE

Sidney Packales, New York, N. Y.

Application April 13, 1956, Serial No. 41,070

Term of patent 7 years

(Cl. D80—5)

Fig. 2

Fig. 1 is a plan view of a gift package ornament display, or similar article, showing my new design, and
Fig. 2 is an edge thereof.

I claim:

The ornamental design for a gift package ornament display or similar article, substantially as shown.
